UNITED STATES PATENT OFFICE

133,711

DESIGN FOR A SUCTION CLEANER CASING OR THE LIKE

Ralph E. Kruck, Springfield, Mass., assignor to
Westinghouse Electric & Manufacturing Com-
pany, a corporation of Pennsylvania

Application February 27, 1941, Serial No. 99,255

Term of patent 14 years

To all whom it may concern:

Be it known that I, Ralph E. Kruck, a citizen
of the United States, residing at Springfield, in
the county of Hampden and State of Massachu-
setts, have invented a new, original, and ornamental
Design for a Suction Cleaner Casing or
the like, of which the following is a specification,
reference being had to the accompanying draw-
ings, forming a part thereof.

Fig. 1 is a front elevational view of a suction
cleaner casing showing my new design, the same
being on a somewhat reduced scale as compared
to the disclosure in Figs. 2, 3 and 4;

Fig. 2 is a perspective view looking down on
the right-hand front corner;

Fig. 3 is a top view; and

Fig. 4 is a side perspective view.

The dominant features of the design reside
in the casing shown in full lines on the drawings.
What I claim is:

The ornamental design for a suction cleaner
casing or the like, substantially as shown and
described.

RALPH E. KRUCK.
